UNITED STATES PATENT OFFICE.

JAMES A. McCREARY, OF CONNELLSVILLE, PENNSYLVANIA.

COKE-OVEN DOOR.

1,121,385.

Specification of Letters Patent. Patented Dec. 15, 1914.

Application filed December 12, 1913. Serial No. 806,308.

To all whom it may concern:

Be it known that I, JAMES A. McCREARY, a citizen of the United States, residing at Connellsville, in the county of Fayette and State of Pennsylvania, have invented certain new and useful Improvements in Coke-Oven Doors, of which the following is a specification.

This invention relates to the general subject of coke oven doors, and has particular reference to a novel and practical door construction having special utility in its application to furnaces of the coke-oven type where the doors are exposed to great heat.

It is a well known fact that the intense heat to which coke oven doors are subjected causes them to warp and crack or otherwise often be damaged beyond repair, so that the usual life of doors of this character is very short.

Accordingly, one of the objects of the present invention is to provide a construction whereby the life of such doors is materially increased, and a distinctive object is to provide a novel and efficient tile-locking means carried by certain portions of the door frame and adjustable from the outside of the door. This latter feature is one of practical importance, as it increases the efficiency of the door under service conditions, and not only facilitates the assembling of the tiles in the door frame, but makes it possible to tighten the tiles without removing the door from the oven and without manual discomfort. In addition to these advantages, it makes possible the use of irregular tile units, and also provides means of adjustment to compensate for shrinkage of the tiles due to their exposure to heat.

With the above and other objects in view, the invention consists in the novel construction, combination, and arrangement of parts, hereinafter more fully described, illustrated, and claimed.

A preferred and practical embodiment of the invention is shown in the accompanying drawings, in which—

Figure 1 is a side elevation of the completely assembled improved coke oven door. Fig. 2 is a cross sectional view on the line 2—2 of Fig. 1. Fig. 3 is an elevation of the skeleton door frame. Figs. 4 and 5 are views of the top and bottom corner tile units employed in the door construction; each view including a face view and pro-

jected top and edge views of one unit. Fig. 6 is a plan view of all of the tile units separated and arranged to show their relative position to each other and to the door frame. Fig. 7 is an enlarged sectional view of a portion of the door frame at one of the cam locking elements. Fig. 8 is an enlarged side elevation of the construction shown in Fig. 7.

Like reference characters designate corresponding parts in the several figures of the drawings.

The present design of coke oven door includes in its organization a main skeleton frame member 1 which is angular in cross-section and preferably of an inverted U-shape, having its lower ends 2 connected by means of a bottom frame bar 3 whose cross section is similar to that of the main frame member 1. As will be observed from the accompanying drawings, the flange portion 4 of the entire door frame F, which includes the main frame member 1 and the bottom frame member 3, projects outwardly, while the opposite flange 5 is disposed at right angles thereto and forms the inner face of the metallic portion of the door. The said frame member 1 is provided with a transversely disposed and centrally located locking frame bar 6 whose side faces 7 converge outwardly from the inner side of the door, while the lower portions 2 of the frame 1 are connected with the bottom frame bar 3 by means of suitable corner reinforcing elements 8. A vertically arranged hanger bar 9 preferably has its opposite ends secured to the flanges 4 of the frame members 1 and 2, and is also connected to the corner reinforcing elements 8 at the lower ends of the door frame by means of the brace arms 10. The said hanger bar 9 has attached to its upper portion a hanger eye 11 to facilitate the lifting and shifting of the door by the carriage riding on a trackway, such as is usually provided for handling doors of this character. For the purpose of preventing the door from falling into the oven or furnace, and positioning it in the opening therein, the projecting side stops 12 are provided, as clearly shown in Fig. 1 of the drawings.

From the foregoing description, it will be apparent that the door frame is especially adapted for carrying a number of independent removable and replaceable refractory tile units to protect the metallic parts thereof.

from the intense heat of the oven, and as shown in the accompanying drawings each tile unit is designated by the reference character 13. The essential structural features of each of the tile units are the same, so a description of the features of one of the several units will suffice for all. The said tiles 13 include a body portion 14 which is beveled at one side, as at 15, and provided 5 with the metal protecting edge flange 16, and are constructed in this manner so that the beveled side 15 can engage with the inclined face 7 of the central locking bar 6, and the adjacent protecting edge flange 16 10 will cover half of the exposed surface of said bar. Accordingly, when a matching lower unit is put in place, the other half of the exposed portion of the locking bar will be covered by its corresponding protecting 15 edge flange. The edges of the tile units that are adjacent the frame members 1 and 2 are also provided with the protecting edge flanges 17, but the frame portion 18 thereof which engages under the flange 4 of the door frame is straight instead of beveled like the side 15, to permit the swinging into place of each of the tile units using the edge of the locking bar 6 as a fulcrum. Each tile is also provided on the frame portion 18 with 20 a plurality of keeper notches 19, the function of which will hereinafter be more fully referred to. Further, in connection with the tile units 13, it will be observed that when all of the said units are in place that when all of the said units are in place that 25 their protecting edge flanges 16 and 17 wholly cover all of the interior metallic parts of the frame members 1 and 2 and the locking bar 6, so that they are not exposed to the intense heat of the furnace.

30 Spaced at suitable intervals and arranged on the frame members 1 and 2, are a plurality of tile-locking devices designated in their entirety by the reference character L. Each of these locking devices include a bearing box 20 suitably secured to the flange 4 of the frame, said box 20 being provided with a plurality of radial notches 21, and also include a locking cam bolt 22 having an exterior tool engaging nut 23 and a locking cam flange 24 on the opposite end of the shank 25 which is journaled within the bearing box 20. The said shank 25 of the locking cam bolt 22 is also provided with a diametrical opening 26 adapted to register 35 with the notches 21 to receive a cotter pin or equivalent fastening 27 placed in one of the said notches on the bearing box to thereby lock the cam bolt against rotary movement in either direction. The flange 4 of the frame members 1 and 2 is necessarily 40 provided with a plurality of cam openings 28 which permit the cam flange 24 to project into bearing engagement with the refractory tile units 13. However, to prevent 45 the cam 24 from breaking or crushing the

tile where it comes in contact therewith, and by its grinding and camming action wearing into the face of the same so that an ineffective lock would result, there is provided a retaining shield plate 29 which is 50 provided with a locking lug 30 adapted to engage in one of the keeper notches 19 on the tile unit. For the purpose of properly positioning the locking lug and locating it in the keeper notch in the tile, and also for 55 preventing the tile from falling into the furnace, the locking plate 29 is provided at its end opposite the lug 30 with a frame engaging extension 31. Therefore, when the cam 34 has been turned into forcible engagement with the retaining plate 29, the lug 31 will securely engage the tile unit and prevent it from dropping from the frame.

From the foregoing description, it will be obvious that in order to assemble the 60 door, all of the cams 24 will be turned around until their small diameters face the space provided for the tile units, then all the tile units can be placed in the frame and into locking engagement with the locking 65 bar 6, which will allow a slight clearance between the frame members and the tile units at both the top and bottom of the door, to permit the insertion of the retaining plate 29. When this has been done, all 70 of the cams 24 will be turned until they forcibly bear against the retaining plates 29 and thereby lock the tile units in the frame, and when the cams are sufficiently tight, a cotter pin or equivalent fastening 75 will be placed in the one of the notches which is in alignment with the axial opening 26 of the cam bolt, thereby holding the cam in rigid contact with the retaining plate. In event the tiles begin to shrink 80 while the door is in position on the oven, it will only be necessary to remove the cotter pin and turn the cams sufficiently to 85 keep the retaining plate always in contact with the tiles, thereby re-securing the tiles 90 in place without removing the door from position.

While the structural characteristics of the various tile units are the same, the designs thereof necessarily differ to suit their 95 particular location in the door frame. This plainly appears in Figs. 4 and 5 and also in Fig. 6, where the upper corner tile units additionally designated by the reference character T are shown with rounded corner 100 portions t, while the lower tile units T' are all of substantially rectangular form, and the upper central units T² have a rounded top portion t² to conform with the curvature 105 of the top of the frame.

110 It is believed that the various features and advantages of the invention will be readily apparent without further description, and that minor changes in details of construction may be resorted to without de- 115

parting from the scope or sacrificing any of the advantages of the invention.

I claim:

- 5 1. A coke oven door including a tile supporting frame, tile units, and a plurality of rotatably adjustable spaced apart edge locking devices arranged about said frame, each tile being engaged by certain of said devices.
- 10 2. A coke oven door including a tile supporting frame, a plurality of independently removable and replaceable tile units carried by said frame, a frame bar for engaging similar edges of all of the tile units, and a plurality of independent edge locking means carried by said supporting frame for engaging the outer edges of each of the tile units.
- 15 3. A coke oven door including a rigid supporting frame, a plurality of independently removable and replaceable tile units carried thereby, a rigid tile-edge-locking member, and a plurality of manually-operated independent tile-edge-locking devices carried by said rigid supporting frame adapted to force said tile units into locking engagement with said rigid tile edge-locking member.
- 20 4. A coke oven door including a tile supporting frame, tile-units carried by said frame, a plurality of locking cams journaled upon said frame and adapted to be rotated to lock said tile-units in position in the frame.
- 25 5. A coke oven door including a tile supporting frame, tile-units carried by said frame, a plurality of locking cams journaled upon said frame, a shield plate interposed between said locking cams and the tile-units, said cams adapted to be rotated into engagement with said plate to force

the latter into locking engagement with the tile-units to hold the same in position in the frame.

6. A coke oven door including a supporting frame having a plurality of cam slots, tile-units carried by said frame and provided with keeper notches, locking cams journaled upon said frame and working in said cam slots, retaining shield plates interposed between said tile-units and the frame, said cams adapted to force the retaining shield plates into the keeper notches in the tiles to hold the same in position in the frame.

7. A coke oven door including a main frame member, a bottom frame member connected to said main frame, a central tile-unit locking frame bar, a hanger bar having brace connections with the frame members and also secured thereto, tile-units carried by said frame, and rotatably adjustable means for engaging the edges of said tile-units for locking the same in position in the frame.

8. A coke oven door including a main frame member, a bottom frame member, a central tile-unit locking frame bar, refractory tiles provided with keeper notches and frame protecting edge flanges, having a locking connection with said central tile-locking frame bar, and auxiliary tile-unit locking means carried by said frame members adapted to secure the tile-units in the door frame at their outer edges.

In testimony whereof I hereunto affix my signature in the presence of two witnesses.

JAMES A. McCREARY.
